Patented Mar. 6, 1917.

Fig. 1.

UNITED STATES PATENT OFFICE.

UBALD HEBERT, OF MANCHESTER, NEW HAMPSHIRE, ASSIGNOR, BY MESNE ASSIGNMENTS, TO DRAPER CORPORATION, OF HOPEDALE, MASSACHUSETTS, A CORPORATION OF MAINE.

AUTOMATIC FILLING-REPLENISHING LOOM.

1,218,257.

Specification of Letters Patent.

Patented Mar. 6, 1917.

Application filed July 3, 1916. Serial No. 107,247.

To all whom it may concern:

Be it known that I, UBALD HEBERT, a citizen of the United States, and resident of Manchester, county of Hillsborough, State 5 of New Hampshire, have invented an Improvement in Automatic Filling-Replenishing Looms, of which the following description, in connection with the accompanying drawing, is a specification, like characters on 10 the drawing representing like parts.

This invention relates to improvements in filling replenishing looms in which a supply of filling carriers is maintained in a 15 hopper from which the filling carriers are transferred successively to the running shuttle by a suitable transfferer, and one object of the invention is to provide means to secure the proper position of the filling carrier during transfer in order that it may 20 be directed into the shuttle in proper position.

The invention in its more specific form relates to a filling replenishing loom of the well known Northrop type in which an in- 25 termittently rotatable hopper is employed carrying a series of filling carriers about its periphery.

More particularly the invention relates to filling replenishing looms making use of 30 filling carriers having feeling slots in the barrel thereof such as are illustrated for example in the patents to William Parker Straw No. 906,748 granted December 15, 1908, No. 1,053,673 granted February 18, 35 1913, and No. 1,092,959 granted April 14, 1914. When this type of filling carrier is employed it is necessary that the slot there- 40 in shall be positioned in a definite relation to the feeler in order that the latter may work properly. Consequently the butts of 45 the filling carriers are provided with suitable positioning means, usually slabbed or flattened surfaces generally in planes at right angles to the longitudinal planes of the slot, and these surfaces are engaged by 50 suitable jaws within the shuttle to retain the filling carriers in position. The filling carriers are carried in the hopper and fed therefrom by the transfferer as upon the call for filling replenishment, but when a 55 filling carrier is forced from the hopper toward the shuttle it frequently rotates more or less and is not infrequently driven into the shuttle jaws in improper position. As

a result the feeler fails to operate or a smash is caused.

Heretofore it has been proposed as in the patent to Alonzo E. Rhoades No. 1,167,363 granted January 4, 1916 to provide a vertically movable device which shall seize the 60 positioning faces of the filling carrier and move down with the filling carrier maintaining it in position until it is forced into the shuttle.

In my prior application Serial No. 76790, 65 filed February 7, 1916, I have also disclosed guiding means which are fixed against vertical movement but which move rearwardly and forwardly and which engage with the filling carrier and prevent rotation of the 70 filling carrier during transfer so that by reason of this engagement as the filling carrier moves downwardly during transfer and thus moves downwardly with respect to the guiding means the filling carrier is held 75 against rotation while at the same time the guiding means moves rearwardly concurrently with the lay, thus enabling the filling carrier readily to be directed into the shuttle in proper position.

The present invention is in its main features subordinate of that of my aforesaid prior application. The present invention presents a guiding means which as in my prior application is fixed against vertical 85 bodily movement but which is pivotally mounted to secure the necessary rearward and forward movement to enable it to move concurrently with the lay during transfer.

In the preferred form of the invention 90 illustrated the guiding means is also pivotally mounted upon the hopper and as shown upon the axis of the hopper.

In the usual type of rotatable hopper wherein the bobbin seats are radial it has 95 been found that the rotative movement of the filling carrier under the action of the transfferer tends to displace the positioned filling carrier as it is presented to the shuttle particularly if the guides for the base of the 100 filling carrier engage the filling carrier as the shuttle comes beneath it.

The invention therefore further consists in a hopper in which the filling carrier seats are inclined to the radii of the hopper combined with a guiding means in which the guiding surfaces or elements form continuations of or are parallel with the filling car-

rier seats of the hopper so that during transfer the positioning elements of the filling carrier will remain inclined to the shuttle whereby the retative influence of the trans-
5 ferrer upon the filling carrier will be neutralized by this inclined arrangement and cause the filling carrier to be properly positioned during the last portion of the thrust of the trans-
ferrer.

10 The present invention also provides a guiding means which receives its movement rearwardly from the downward thrust of the filling carrier being transferred and its forward movement under the action of a
15 spring so that no direct connection with the trans-
ferrer or a positive connection with any other moving part of the loom is necessary.

Other objects of the invention will more
20 fully appear from the accompanying drawings and will be pointed out in the annexed claims.

The drawings illustrate so much of a filling replenishing loom as is necessary to show the application of the present invention thereto.

In the drawings:

Figure 1 is an end elevation partly in section of a portion of a loom embodying one of the preferred forms of my invention, and,

Fig. 2 is a vertical sectional view on line 2-2 Fig. 1.

In general construction the loom may be
35 and preferably is of the usual Northrop type of automatic filling replenishing loom including a rotatable battery, feeder or hopper comprising parallel disks between which the filling carriers, such as bobbins, are
40 mounted in a circular series. The disk 1 which is shown herein is provided with seats 2 having their walls 3 extending in a direction inclined to the radii of the hopper.

The hopper is rotatably mounted upon a
45 shaft or stud 4 rigidly secured to the usual hopper stand 5 which is itself secured to the loom frame. The circular flange 6 on the hopper stand surrounding the disk 1 protects the heads of the filling carriers or
50 bobbins and retains them in place until they reach substantial transferring position from which point on the bobbins are retained in their seats by a bobbin support 7 yieldably mounted upon a stud 8 projecting from the
55 hopper stand. This bobbin support yields upon passage of the bobbin from the hopper and serves also to force the bobbin in contact with an abutment 9 which directs the bobbin in its passage from the hopper into
60 the running shuttle.

The abutment 9 is secured to the hopper stand and preferably presents a curved face concentric with the path of the trans-
ferrer 10 which is pivotally mounted upon a stud
65 11* on the hopper stand. The trans-
ferrer 10

is of the well known type, being provided with a depending arm 11 through which it is actuated upon call for filling replenishment and with a head 12 having a curved face 13 adapted to engage the base of the
70 bobbin. The trans-
ferrer is normally ele-
vated through the action of a spring 14 and is depressed to effect transfer through the usual connections to the depending arm 11.

The hopper may be rotated by any suitable mechanism to bring the bobbins successively into transferring position. A usual type of actuating mechanism which is illustrated herein comprises a dog 15 pivotally mounted upon a stud 16 carried by the
75 transfer arm, said dog having a tooth 17 adapted to engage the teeth of a ratchet wheel 18 which is integral with or secured to the hopper.

Upon the downward movement of the
80 transfer arm to thrust a bobbin into the shuttle the dog drops from one tooth to another and upon the upward movement of the transfer arm causes the rotation of the disk or hopper one step to bring the leading bobbin of the series into contact with the abutment 9 and thus in position for transfer. The reverse rotation of the hopper is prevented by a counterweighted pawl 19
85 preferably mounted upon a stud 20 projecting from the hopper stand and having its opposite end engaging the teeth upon the ratchet wheel 18 as is usual in constructions
90 of this character.

The filling carrier or bobbin 21 for the
100 transfer of which the present invention is designed is provided with a feeling slot 22 extending into or through the barrel of the bobbin at a short distance from its base. The base of the bobbin is provided with the
105 usual rings 23 and at its end with a position-
ing instrumentality, preferably parallel slabbed positioning faces 24 adapted to be engaged by one or more guides in the shuttle to retain the feeling slot 22 in horizontal position. The shuttle 25 is provided with the usual clamping jaws 26 and in addition thereto upwardly extending slightly flaring and preferably resilient guides 27
110 to engage the positioning faces upon the base of the bobbin as the bobbins are thrust into the shuttle and to position the bobbin in the shuttle and retain it thereafter in proper position. The shuttle is of course carried by the usual lay and is received at the end of its flight by shuttle boxes 28 of
115 usual character.

In looms of this character a narrow space intervenes between the hopper and the shuttle when the latter is in transferring position and the action of the trans-
ferrer upon the bobbin which is in rolling contact with the abutment 9 tends to rotate the bobbin so that the positioned faces will not be prop-
erly engaged by the guides 27 of the shuttle,
120

furthermore it sometimes happens during transfer that one of the guides 27 strikes the edge of the faces 24 upon the bobbin bases and rotates the bobbin so that it is 5 improperly thrust into the shuttle jaws or occasions a smash.

In the present invention there is provided a guiding means which is pivotally mounted preferably on the hopper and which is 10 fixed against bodily vertical movement. This guiding means in the construction illustrated operates upon the filling carrier intermediate of the hopper and shuttle to preserve the rotative position of the filling carrier unchanged as it is transferred to the 15 shuttle and which preferably is adapted to be moved rearwardly and concurrently with the movement of the lay as the latter approaches transferring position so that the base of the filling carrier will be guided positively until it is thrust into the jaws of the shuttle. The movement of the guiding means also serves to prolong the period in 20 which the guiding means is in registry with the shuttle and aids in insuring proper transfer.

A preferred form of guiding means illustrated in the accompanying drawing comprises a conveyer 30 in the form of a chute having parallel walls 31 which when in 30 normal position form continuations of the walls 3 of the recesses 2 of the hopper. This conveyer may conveniently be formed as the integral offset portion of an arm 32 pivotally mounted upon the shaft 4 of the hopper. In the preferred embodiment of the invention illustrated herein the hopper stand is provided with a cylindrical offset portion 33 providing a hub 34 for the cylindrical bearing member 35 of the arm 32. A radially offset portion 36 preferably is also provided to receive the arm 32 and to provide for a limited movement thereof. A spring 37 seated against the wall of the offset portion 45 36 and bearing against a lug 38 upon the arm 32 serves normally to maintain the conveyer 30 with its walls 31 in alinement with and forming continuations of the walls 3 of the bobbin seats 2 as aforesaid. The arm 32 50 may be guided by a boss extending through a slot in the stand and having a washer 32 secured to its end to overlie the slot.

Where as in the present construction the walls of the bobbin seat are inclined to the 55 radii of the hopper the action of the transfer arm in thrusting a bobbin from the hopper into the shuttle will rotate the hopper slightly since the bobbin is normally held in contact with the abutment 9 by the bobbin support 7. By reason of the fact that the walls 31 of the conveyer are similarly inclined to the radii of the hopper the action of the transferrer arm moves the conveyer laterally against the force of the 60 spring 37 as the bobbin is thrust toward the

shuttle and causes the conveyer to move in consonance with the lay as the latter approaches final position. By reason of this fact the period in which the conveyer and shuttle are in registry is slightly prolonged. 70

While the construction above described constitutes a preferred embodiment of my invention it is to be understood that this embodiment is illustrative merely and not restrictive and that various other means for 75 directing the bobbin from the hopper to the shuttle may be employed within the meaning and scope of the following claims.

It is also to be understood that while the invention has been described particularly 80 with reference to its use upon bobbins having feeling slots in their barrels, the invention is also useful for insuring proper transferring of bobbins of ordinary character into the running shuttle.

Having thus described my invention what I claim as new and desire to secure by Letters Patent is:

1. A filling replenishing loom comprising a hopper adapted to contain a plurality of 90 filling carriers, a transferrer and means for actuating the same to thrust a filling carrier into the shuttle, and rearwardly and forwardly movable guiding means fixed against vertical bodily movement and provided with 95 a chute acting to receive and direct the filling carrier during its passage from the hopper to the shuttle, said guiding means being movable rearwardly into registry with the shuttle by the filling carrier as the latter is forced from the hopper into the shuttle by the transferrer.

2. A filling replenishing loom comprising a hopper adapted to contain a plurality of 105 filling carriers, a transferrer and means for actuating the same to thrust a filling carrier into the shuttle, and yieldable means provided with inclined guiding instrumentalities located intermediate of said hopper and shuttle and normally maintained in communicative relation to said hopper and movable into registry with the shuttle by the filling carrier as the latter is forced from the hopper into the shuttle by the transferrer.

3. A filling replenishing loom comprising 110 a hopper adapted to contain a plurality of filling carriers, a transferrer and means for actuating the same to thrust a filling carrier into the shuttle, pivotally mounted guiding means for said filling carriers located intermediate of said hopper and shuttle, resilient means for normally maintaining said guiding means in communicative relation with the hopper and acting to permit said guiding means to be moved rearwardly into registry with the shuttle by the filling carrier as the latter is forced from the hopper into the shuttle by the transferrer.

4. A filling replenishing loom comprising 115 a rotatable hopper having peripheral re-

cesses to support filling carriers, a trans-
ferrer and means for actuating the same
to thrust the filling carrier into the shuttle,
guiding means intermediate of said hopper
5 and shuttle pivotally movable about the
axis of said hopper, and means for nor-
mally maintaining said guiding means in
communicative relation with a recess in said
hopper and acting to permit said guiding
10 means to be moved rearwardly into registry
with the shuttle by the filling carrier as the
latter is forced from the hopper into the
shuttle.

5. A filling replenishing loom comprising
15 an intermittently rotatable hopper provided
with peripheral filling carrier seats inclined
to the radii of the hopper, a transerrer and
means for actuating the same to thrust a
filling carrier from said hopper into the
20 shuttle, and a conveyer intermediate of said
hopper and shuttle having walls normally
forming continuations of the walls of said
filling carrier seats and acting to receive the
filling carrier as it is moved from the hop-
25 per and to preserve the rotative position of
said carrier unchanged as it is transferred
to the shuttle.

6. A filling replenishing loom comprising
an intermittently rotatable hopper provided
30 with peripheral filling carrier seats inclined
to the radii of the hopper, a transerrer and
means for actuating the same to thrust a
filling carrier from said hopper into the
shuttle, and a conveyer intermediate of said
35 hopper and shuttle having walls normally
forming continuations of the walls of said
filling carrier seats and acting to receive the
filling carrier as it is moved from the
hopper and to preserve the rotative position
40 of said carrier unchanged as it is trans-
ferred to the shuttle, said conveyer being
movable rearwardly into registry with the
shuttle by the movement of the filling car-
rier under the influence of the thrust of the
45 transerrer.

7. A filling replenishing loom comprising
an intermittently rotatable hopper provided
50 with peripheral filling carrier seats inclined
to the radii of the hopper, a transerrer and
means for actuating the same to thrust a
filling carrier from said hopper into the
shuttle, and a conveyer, pivotally mounted
55 upon the axis of said hopper and located
intermediate of said hopper and shuttle,
having walls normally forming continuations
of the walls of said filling carrier seats
and acting to receive the filling carrier as
60 it is moved from the hopper and to pre-
serve the rotative position of said carrier
unchanged as it is transferred to the shuttle.

8. A filling replenishing loom comprising
an intermittently rotatable hopper provided
65 with peripheral filling carrier seats inclined
to the radii of the hopper, a transerrer and
means for actuating the same to thrust a

filling carrier from said hopper into the
shuttle, and a conveyer, pivotally mounted
upon the axis of said hopper and located in-
termediate of said hopper and shuttle, hav-
ing walls normally forming continuations
70 of the walls of said filling carrier seats and
acting to receive the filling carrier as it is
moved from the hopper and to preserve the
rotative position of said carrier unchanged
as it is transferred to the shuttle, said con-
veyer being movable rearwardly into regis-
try with the shuttle by the movement of the
filling carrier under the influence of the
thrust of the transerrer.

9. A filling replenishing loom comprising
80 a hopper adapted to contain a plurality of
filling carriers, a transerrer and means for
actuating the same to thrust a filling car-
rier into the shuttle, an abutment to guide
the filling carriers in their passage from
85 the hopper to the shuttle during transfer,
and pivotally mounted guiding means move-
able rearwardly and forwardly and pro-
vided with instrumentalities to engage with
and to preserve the rotative position of the
90 carrier as it is transferred to the shuttle.

10. A filling replenishing loom comprising
a hopper adapted to contain a plurality of
filling carriers, a transerrer and means for
actuating the same to thrust a filling car-
95 rier into the shuttle, an abutment to guide
the filling carriers in their passage from
the hopper to the shuttle during trans-
fer and a pivotally mounted conveyer in-
100 termediate of said hopper and shuttle hav-
ing guiding means to preserve the rotative
position of the carrier unchanged as it is
transferred to the shuttle.

11. A filling replenishing loom comprising
an intermittently rotatable hopper pro-
105 vided with peripheral bobbin seats inclined
to the radii of the hopper, a transerrer and
means for actuating the same to thrust a
filling carrier from said hopper into the
shuttle, an abutment to guide the filling
110 carriers in their discharge from the hopper
to the shuttle and yieldable conveying
means movable by the filling carrier under
the thrust of the transerrer located inter-
mediate of the hopper and shuttle to pre-
115 serve the rotative position of the carrier
unchanged as it is transferred to the shuttle.

12. A filling replenishing loom comprising
a hopper adapted to contain a plurality of
filling carriers, a transerrer and means
120 for actuating the same to thrust a filling
carrier into the shuttle, and pivotally sup-
ported guiding means fixed against vertical
bodily movement and acting to engage the
filling carrier and to preserve the rotative
125 position thereof during its passage from the
hopper to the shuttle.

13. A filling replenishing loom comprising
a hopper adapted to contain a plurality
130 of filling carriers, a transerrer and means

for actuating the same to thrust a filling carrier into the shuttle, and means pivotally supported upon said hopper adapted to engage the filling carrier and to preserve the 5 rotative position thereof during its passage from the hopper to the shuttle.

14. A filling replenishing loom comprising a hopper adapted to contain a plurality of filling carriers, a transferrer movable in 10 a circular arc for transferring a carrier from the hopper to the shuttle, and a movable conveyer intermediate of the hopper and shuttle having means for preserving the rotative position of the filling carrier as 15 it is transferred from the hopper to the shuttle and moved rearwardly by said filling carrier under the thrust of the transferrer.

15. A filling replenishing loom comprising a hopper adapted to contain a plurality of filling carriers, a transferrer movable in a circular arc for transferring a carrier from the hopper to the shuttle, a stationary abutment having a curvature concentric 20 with the path of the transferrer to guide the bobbins in their discharge from the hopper to the shuttle, and a movable conveyer intermediate of the hopper and shuttle having means for preserving the rotative position 25 of the filling carrier as it is transferred from the hopper to the shuttle and moved rearwardly by said filling carrier under the thrust of the transferrer.

16. A filling replenishing loom comprising a rotary hopper provided with peripheral bobbin seats inclined to the radii of the hopper, a transferrer movable in a circular path for thrusting the filling carriers 30 from the hopper into the shuttle, a stationary abutment having a curvature concentric with the path of the transferrer to guide the filling carriers in their discharge from the filling carrier bobbin seats during transfer, and a conveyer intermediate of said hopper 35 and shuttle having guiding walls acting normally to form continuations of the walls of said filling carrier seats, said conveyer being movable by said filling carriers under the thrust of the transferrer into registry with the shuttle.

50 17. A filling replenishing loom comprising a hopper having a circular head with a radial offset portion providing a recess, a shaft mounted in said head, a rotatable hopper having peripheral filling carrier receiving recesses and pivotally mounted upon said shaft, and a conveyer located intermediate of the hopper and shuttle having a

supporting arm located in the radial recess in said head and means for thrusting the filling carrier from said hopper into said conveyer.

60 18. A filling replenishing loom comprising a hopper having a circular head with a radial offset portion providing a recess, a shaft 65 mounted in said head, a rotatable hopper, having peripheral filling carrier seats inclined to the radii of said hopper, a conveyer located intermediate of the hopper and shuttle and having walls adapted to form continuations of the walls of the filling carrier 70 seats, said conveyer having a supporting arm located in the recess in said head, a spring for normally maintaining the conveyer in registry with the filling carrier 75 seats in the hopper and a transferrer adapted to thrust the filling carrier from the hopper into the shuttle whereby the movement of the filling carrier under the thrust of the transferrer will position the conveyer in 80 registry with the shuttle.

85 19. A filling replenishing loom comprising a hopper adapted to contain a plurality of filling carriers provided with positioning instrumentalities, a transferrer and means for actuating the same to thrust a filling carrier from the hopper into the shuttle and pivotally supported guiding means fixed 90 against vertical bodily movement and acting to engage with the positioning instrumentalities of a filling carrier during transfer whereby as the filling carrier moves along the guiding means it will be prevented from rotation with respect thereto and delivered to the shuttle in predetermined position.

95 20. A filling replenishing loom comprising a hopper having a circular series of holders to receive the bases of filling carriers having a feeler slot in the barrel and 100 a guiding instrumentality at right angles to the plane of said slot, a transferrer and means for actuating the same to thrust said filling carriers successively into the shuttle and pivotally supported guiding means 105 fixed against vertical bodily movement and acting to engage the positioning instrumentality on the filling carrier being transferred whereby as the filling carrier moves along the said pivotally supported guiding 110 means it will be prevented from rotation with respect thereto and delivered to the shuttle in predetermined rotary position.

In testimony whereof, I have signed my name to this specification.

UBALD HEBERT.

It is hereby certified that in Letters Patent No. 1,218,257, granted March 6, 1917, upon the application of Ubald Hebert, of Manchester, New Hampshire, for an improvement in "Automatic Filling-Replenishing Looms," an error appears in the printed specification requiring correction as follows: Page 5, line 43, claim 16, strike out the word "bobbin"; and that the said Letters Patent should be read with this correction therein that the same may conform to the record of the case in the Patent Office.

Signed and sealed this 3d day of April, A. D., 1917.

[SEAL.]

F. W. H. CLAY,

Acting Commissioner of Patents.

Cl. 139—85.
